UNITED STATES PATENT OFFICE

2,464,323

PUNCH FOR FLUTING GUN-BARREL
CHAMBERS

John W. Lee, Dayton, Ohio, assignor to General
Motors Corporation, Detroit, Mich., a corpora-
tion of Delaware

Application March 13, 1946, Serial No. 654,166

2 Claims. (Cl. 78—1)

1

My invention relates to a method and apparatus for use in fluting of gun barrel chambers.

The cartridge chamber of light weapons such as rifles and machine guns is often provided with a number of grooves or "flutes" running rearwardly from a location near the origin of the rifling to a predetermined distance from the breech end of the barrel. This fluting is intended to facilitate extraction of empty cartridge cases, the action being due to gas from the fired cartridge which flows back along the flutes to act under pressure upon the outer surface of the cartridge casing. If the fluting is properly designed it has been found that the extraction of cartridge cases can be greatly facilitated by this means.

An object of my invention is to provide an improved coining punch for fluting gun barrel chambers. Another object is to provide an improved method of making coining punches for gun barrel chambers which overcomes the difficult machining problems previously encountered in the making of such fluting punches.

With the above and other objects in view which will become apparent as the description proceeds, I will describe my invention in connection with the appended figures of drawing in which:

Figure 1 is a perspective view of coining punch made in accordance with my invention,

Figure 2 is a longitudinal cross section view of a gun barrel chamber showing my punch therein,

Figure 3 is a cross section taken on line 3—3 of Figure 2,

Figure 4 shows a fluting chamber after the punch is withdrawn and the fluting operation is completed.

The problem of cartridge case extraction is of concern even in nonautomatic weapons since cartridge cases occasionally tend to jam in the barrel after firing, but it is of particular importance in automatic weapons where extraction at high firing rates often takes place while there is still considerable pressure of expanding gases inside the chamber, even though the bullet has left the rifle. The force of these gases may still be in the order of magnitude of several thousand pounds per square inch, so that the cartridge case may still be in an expanded state when extraction commences, producing considerable resistance to extraction, with a consequent tendency toward jamming of the weapon. The fluting is provided so that some gas under the same high pressure may be forced around the outside of the cartridge case between it and the chamber walls, to counter-balance the expansive force of the residual gases still remaining within the case at the time extraction commences.

Due to the fact that the contour of the cartridge chamber of many modern guns is in a series of steps to accommodate the different diameters of the cartridge case, bullet and barrel bore, the

2

problem of fluting the chamber presents some difficulty and comparatively complicated equipment is required to cut the flutes. Coining the flutes is much more simple but to make a punch of such irregular contour by conventional machining methods involves some difficulty; moreover the punches are good for only a limited number of operations before they are worn beyond the required limits of tolerance. It will be understood that it is possible to use a punch for producing the fluting grooves in this case because there is a slight but definite taper from the gun barrel chamber converging from the breech toward the muzzle.

15 I overcome the above difficulties by first turning a plug 1 to the exact contour of chamber to be fluted, then a number of flats as shown at 2 and 3 are machined on the plug 1. By properly cutting the flats, not only are the desired depth and width of the flutes obtained but also a sloping side is developed as shown at 6. This has the effect of enhancing penetration circumferentially outward from the grooves so that the gases may penetrate between the chamber wall and the cartridge case, due in part to the reduced angle between the side wall of the flute and the wall of the chamber, and in part to reflection of the shock wave of the gas under high pressure from the opposite sloping wall of the flute, which is 20 by this configuration directed toward the opposite lower edge of the flute with sufficient velocity to aid in penetration of the gases. This penetration is highly desirable in increasing the effective gas pressure and the gas lubrication between the cartridge casing and the chamber wall, to facilitate extraction of the cartridge.

The punch is provided with centering nose 4 adapted to center the punch in the bore 5 of the gun, after which force is applied to the end of the punch by any known means to produce the flutes.

40 The number of corners on the punch can be reduced if desired, to $\frac{1}{2}$ of the number of flutes desired, in order to reduce the pressure required to coin the flutes. In this case it is necessary to index the punch in known fashion to produce the total desired number of flutes by a second operation.

45 Figure 4 shows a completely fluted chamber made in this case by 2 coining operations of a four cornered punch such as is shown in Figure 1, to form eight grooves 6.

In the event that, due to the dimensions of the fluting and the nature of the barrel material, the displaced material raises ridges on the sides of 50 the flutes of sufficient height to be objectionable, these ridges can be removed by a suitable subsequent operation such as reaming.

55 It is apparent that the surfaces 2, 3, etc., need not be flat planar surfaces, as they may equally well be formed by a rotating tool so as to be curved

surfaces without affecting the principal or operation of my invention.

I claim:

1. A fluting punch for producing fluting grooves in gun chambers comprising a cylindrical portion and a series of axially aligned, progressively smaller truncated pyramidal portions, said pyramidal portions being united to each other in a base-to-truncated-end relationship with corresponding parts of each pyramidal portion lying in a radial plane extending through the axis of the cylindrical portion.

2. A fluting punch for producing fluting grooves in gun chambers comprising a cylindrical plug portion, a series of axially aligned, progressively smaller truncated pyramidal portions extending from said cylindrical portion, said pyramidal portions being joined together in a base-to-truncated-end relationship, each said pyramidal portion having a plurality of sides and relatively narrow faces between adjacent sides, the correspond-

ing parts of each pyramidal portion being aligned whereby said relative narrow faces form continuous flute-forming means.
